Patented Sept. 14, 1971

221,848

FISHING LURE BODY

James W. Omdall, Jr., Box 93, Palmyra, Wis. 53156

Filed Aug 4, 1970, Ser No 24,291

Term of patent 14 years

Int. Cl. D22—05

U.S. Cl. D22—27

FIG. 1

FIG. 2

FIG. 3

FIG. 4

FIG. 5

FIG. 1 is an elevational view showing the design of a fishing lure body;

FIG. 2 is a top plan view of the fishing lure body;

FIG. 3 is a bottom plan view of the fishing lure body;

FIG. 4 is a front elevational view of the body; and

FIG. 5 is a rear elevational view of the body.

The side of the fishing lure opposite to that shown in FIG. 1 is identical to that of FIG. 1.

I claim:

The ornamental design for a fishing lure body, substantially as shown and described.
